The ornamental design for a handbag, as shown and described.

(22) Filed: Apr. 3, 2018

(80) Hague Agreement Data

DESCRIPTION

Int. Filing Date: Apr. 3, 2018

1. Handbag

Int. Reg. No.: DM/100662

The patent or application file contains at least one drawing executed in color. Copies of this patent or patent application publication with color drawing(s) will be provided by the Office upon request and payment of the necessary fee.

Int. Reg. Date: Apr. 3, 2018

FIG. 1.1 is a perspective view of the handbag;

Int. Reg. Pub. Date: Oct. 5, 2018

FIG. 1.2 is a front view thereof;

(30) Foreign Application Priority Data

FIG. 1.3 is a back view thereof;

Nov. 8, 2017 (EM) 004498970

FIG. 1.4 is a right side view thereof;

(51) LOC (12) Cl. 03-01

FIG. 1.5 is a left side view thereof;

(52) U.S. Cl.

FIG. 1.6 is a top perspective view thereof, where the bottom of the handbag is not visible; and

USPC D3/232

FIG. 1.7 is a bottom view thereof.

(58) Field of Classification Search

In FIG. 1.7, the portions of the handbag shown in purple form no part of the claimed design.

USPC D3/201, 217, 232–233, 240–243,

The broken lines on the periphery and surface of the handbag and on the handles of the handbag represent

D3/245–247, 249–253, 318, 321, 322

stitching and form a part of the claimed design.

CPC A45C 1/024; A45C 3/06

See application file for complete search history.
